UNITED STATES PATENT OFFICE.

ARTHUR E. ROCKOLA, OF SANDFORD DEEN, SASKATCHEWAN, CANADA.

GRAIN-PICKLER.

1,344,148.

Specification of Letters Patent. Patented June 22, 1920.

Application filed October 10, 1919. Serial No. 329,677.

To all whom it may concern:

Be it known that I, ARTHUR E. ROCKOLA, a subject of the King of Great Britain, residing at Sandford Deen, in the province of 5 Saskatchewan and Dominion of Canada, have invented certain new and useful Improvements in Grain-Picklers, of which the following is a specification.

This invention is a grain pickler and has 10 for its principal object the production of an efficient means for thoroughly moistening and mixing the grain with a suitable solution, such for instance as formalin.

Another object of this invention is the 15 production of a grain pickler, wherein a hopper is provided including a depending casing within which is included a rotary agitator causing the grain and solution deposited thereon to be thoroughly mixed and 20 throwing the moistened grain into other receiving and discharging means, causing the grain and solution to be further mixed.

Another object of this invention is the 25 production of a grain pickler wherein a plurality of cones are positioned slightly below corresponding inverted frusto-conical collars so that grain passing through the casing will be thoroughly mixed upon engaging and disengaging these elements.

30 A still further object of this invention is the production of a grain pickler wherein the agitator has a plurality of fins thereon adapted to be engaged by the grain to be efficiently rotated for throwing the grain 35 therefrom by centrifugal force, while the discharge nozzle is so arranged that the spray issuing therefrom will also be directed onto the agitator to be mixed with the grain as the same is being thrown therefrom.

One practical form of construction and assembly of the present invention will be hereinafter described, and is illustrated in the drawing, in which:—

45 Figure 1 is a side elevation of the grain pickler complete.

Fig. 2 is a horizontal section taken on the line 2—2 of Fig. 1.

50 Fig. 3 is a vertical section through the hopper and casing and operating elements therein.

Fig. 4 is an enlarged fragmentary sectional view through the upper end of the

agitator with the deflector head and spray nozzle illustrated also.

Fig. 5 is a section taken on the line 5—5 of Fig. 3.

Fig. 6 is a bottom plan view of the rotary agitator.

In the preferred embodiment of the present invention about to be specifically described, the main supporting frame comprises horizontal portions 10 having depending legs 11 at their ends. There are two of such portions 10 and it will be noted that 5 the legs 11 of each portion are provided with a longitudinally extending brace 12. Supporting bars 13 are carried by the horizontal portion 10 of the same as shown in Fig. 2, although a particular form of supporting frame has been disclosed, it is obvious that any other desired or suitable form may be included without departing from the spirit of the present invention. A supply tank 14 is secured as shown at 15 70 upon the horizontal portions 10 adjacent one end of the frame as illustrated in Figs. 1 and 2. This tank may be of any desired construction and is provided with a cap 16. It is intended that any suitable solution for 75 treating the grain or pickling the same may be provided, such for instance, as formalin which is carried within the tank 14 when the device is ready for use. The pipe 17 leads from the tank and passage through the pipe 80 is controlled by a suitable valve 18 having a second pipe 20 leading therefrom. A suitable union 21 is employed for supporting and connecting the horizontal pipe 23 upon the pipe 20. The hopper 24 has a substantially cylindrical downwardly extending casing 24' projecting from its lower portion to be detachably received in the top of the casing 25 and supported thereon by a flange 23', so that the hopper may be readily removed. The casing 25 is supported by suitable straps 26 upon the bars 13, whereby the casing and hopper are efficiently supported upon the main frame of the device. The horizontal pipe 23 extends through the casing 25 85 intermediate its upper and lower ends as shown in Fig. 3. In order to regulate the size of the cone of grain which is deposited upon the rotary agitator to be hereinafter described, there is provided a regulating 90 cone 27 having a rod 28 extending from the

55

90

95

100

105

apex thereof. The upper end of the rod is screw threaded as shown at 29 and is carried by the nut 30 mounted upon the transverse bridge 31 carried by the upper end of the hopper 24.

A crank 32 extends from the nut 30 so that by swinging the crank the nut 30 may be rotated upon the threaded upper end of the rod 28 for adjusting vertically the cone 27. The stem 28 is also provided with a bearing 33 against which one end of the coil spring 34 bears, the opposite end of the spring bearing upon the bridge 31 for yieldably holding the cone 27 in its lowermost position. In order to guide the movement of the cone 27 a rocking loop 35 has one end pivotally journaled as shown at 36 within the casing 24, while the opposite end of this loop 35 is carried by the cone 27 as shown 20 at 37. Therefore the loop is pivotally mounted upon the casing and pivotally connected to the cone 27, thus allowing the cone to be moved upwardly or downwardly a slight distance as may be desired, although 25 the cone 27 will be held from swinging to one side by the force of grain falling thereon when the same is in use.

The spray nozzle 38 is connected by a joint 39 with the horizontal feed pipe 23 this 30 spray nozzle has apertures 40 in its upper end, while a deflector head 41 is supported upon the upper end of the spray nozzle 38 and overhangs this end as shown in Fig. 4. It is to be noted that the lower end of the 35 hopper 24 terminates adjacent the lower end of the head 41 whereby grain is discharged directly against the agitator, to be presently described.

The rotary agitator comprises a conical body 42 having its neck 43 embracing the nozzle 38. The base 44 fits within the lower portion of the conical body 42 as illustrated in Fig. 6 and is held against downward displacement by a bearing 45 carried 45 upon the nozzle 38. It will be noted, however, that the rotary agitator is free to rotate upon the nozzle. A plurality of concaved fins 46 are fixed upon the upper surface of the conical body 42 as shown in Fig. 50 it being noted that these fins 46 are comparatively broad at their outer ends and taper toward their inner ends, as they extend toward the apex of the conical body 42 of the rotary agitator and are secured to the 55 lower edge of the deflector 41. This rotary agitator is carried directly below the distributing cone 27 and for this reason as grain is discharged from the cone 27 it will strike the concaved fins 46 of the rotary agitator, 60 thus causing the agitator to revolve upon the nozzle 38 thereby the grain will be thrown by centrifugal force from the agitator. At the same time the valve 18 may be regulated to permit the solution to pass from the tank 65 14 through pipes 17, 20 and the union 21 and

pipe 23 to the nozzle 38. This solution will be discharged through apertures 40 in a spray-like formation against the under surface of the head 41 whereby it will be deflected downwardly onto the rotary agitator 70 to be thoroughly mixed with the grain which at this time is causing the agitator to be revolving and is being thrown outwardly from the agitator. A pair of spaced inverted substantially frusto-conical collars 47 are carried within the casing 25 below the pipe 23 as shown in Fig. 3. Supporting strands 48 are carried by these collars 47 and deflector cones 49 are carried by these strands 48, spaced from each other. The upper ends of 80 the cones extend into the lower portions of the collars 47 whereby grain discharged from the rotary agitator will first pass through the upper collars and will then be deflected by the upper cones and subsequently will pass through the lower collar and then be deflected by the lower cone and finally will be discharged from the lower end of the casing 25. With this torsional movement of the grain, which is being continually thrown backward and forward and caused to rotate upon the inclined surfaces, the grain will be efficiently and thoroughly mixed with the solution directed into engagement therewith. 95

When the device is in operation, the tank 14 is first filled with a suitable solution, the valve 18 at this time being closed. The device to all appearances will be the same as shown in Fig. 1. It should be noted that 100 the casing 25 is provided with a peep opening 25' adjacent the lower portion of the hopper 24, thus allowing the operator to easily see the rotary agitator and to determine the amount of spray being deposited thereon and also to determine the relative position of the distributing cone 27 with respect to the rotary agitator. The operator may then pour wheat into the 105 hopper 24 and it will be noted that this 110 wheat will strike upon the distributor hood 27 being distributed therefrom in a cone-like formation. If the hood 27 be raised at a considerable distance above the rotary agitator, the cone of grain will be comparatively large where it strikes the rotary agitator although if the cone 27 be lowered, the cone of grain striking the agitator will be reduced. It is assumed that the position 115 shown for instance in Fig. 3 would be about 120 correct for ordinary operation. As this wheat or other grain strikes upon the rotary agitator it must engage the concaved fins 46, thus rotating the agitator. Simultaneous with this action, the valve 18 will have been 125 opened, thus causing the solution to be passed from the nozzle and deflected downwardly by the deflector head 41 onto the rotary agitator. This solution will be mixed 130 with the grain which is then falling onto 135

the agitator and together they will be thrown outwardly from the agitator by centrifugal force. This moistened grain will be caught by the upper collar and then 5 fall therethrough onto the upper cone. This upper cone will direct the grain outwardly again to be caught by the lower collar, which in turn will direct the grain downwardly onto the lower cone and thence the grain 10 will be discharged from the casing. Thus if the grain being passed through the casing is not entirely moistened while on the rotary agitator, obviously the manner in which the grain will be turned over during its 15 movement down from the casing will cause all surfaces to be exposed so that the surfaces will be effectively moistened by the solution. It will therefore be seen that a very efficient grain pickler has been produced wherein the surfaces will be agitated to allow the solution to efficiently moisten 20 the surfaces thereof as set forth.

The foregoing description and the accompanying drawings have reference to what 25 may be considered to be the approved or preferred form of my invention. I desire it to be understood that I may make such changes in the construction, combination and arrangement of parts, materials, dimensions, et cetera, as may prove expedient and fall within the scope of the appended 30 claims.

Having thus fully described my invention what I claim as new and desire to 35 secure by Letters Patent, is:—

1. In a device of the character described, the combination of a hopper having a casing depending therefrom, a liquid supply means 40 including a vertical nozzle having apertures at the upper portion thereof, a deflector hood carried upon the upper end of said nozzle, and a rotary agitator rotatably mounted upon said nozzle below said deflector hood whereby grain directed onto 45

the rotary agitator will be thrown therefrom as the agitator rotates and will be mixed with the liquid dispensed onto the agitator.

2. In a device of the character described, the combination of a hopper having a casing depending therefrom, a liquid dispensing means including a nozzle having apertures therein, a deflector head overhanging the apertures for directing the liquid dispensed from the nozzle, a rotary agitator including 50 a conical body having a neck embracing said nozzle, a bottom for said body rotatable on the nozzle for supporting the agitator, and a plurality of concaved fins mounted on said conical body as and for the purposes set 55 forth.

3. In a device of the character described, the combination of a hopper having a casing depending therefrom, a liquid supply means including a nozzle having apertures therein, 60 a rotary agitator mounted upon said nozzle below the apertures, and means for deflecting the liquid downwardly upon said rotary agitator.

4. In a device of the character described, 70 the combination of a hopper having a casing depending therefrom, a rotary agitator carried in the upper portion of said casing, a liquid supply means communicating with the rotary agitator, inverted substantially 75 frusto-conical collars carried within said casing and spaced apart, spaced apart cones carried within said casing and extending into the rear portions of the collar, whereby grain deposited onto the collars will fall 80 onto the cones and be deflected downwardly as and for the purposes set forth.

In testimony whereof I affix my signature in presence of two witnesses.

ARTHUR E. ROCKOLA.
